Primary Examiner — Mehri F Bajoul(74) *Attorney, Agent, or Firm* — Harris Beach Murtha Cullina PLLC(57) **CLAIM**

The ornamental design for a puzzle board set as shown and described.

DESCRIPTION

FIG. 1 is a top perspective collapsed view of puzzle board set in accordance with the new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a left side elevational expanded view thereof;

FIG. 9 is a top perspective expanded view thereof; and,

FIG. 10 is top perspective exploded view thereof.

The broken lines in the drawings depict portions of the puzzle board set that form no part of the claimed design.

1 Claim, 10 Drawing Sheets(56)
